Primary Examiner — Antoine D Davis(74) *Attorney, Agent, or Firm* — Kauth, Pomeroy, Peck & Bailey LLP(57) **CLAIM**

The ornamental design for a measuring instrument, as shown and described.

DESCRIPTION

FIG. 1 is a first perspective view of a measuring instrument in accordance with our design.

FIG. 2 is another perspective view thereof showing separation of a first part of the instrument from a second part of the instrument.

FIG. 3 is a side elevation view thereof.

FIG. 4 is a side elevation view thereof showing separation of a first part of the instrument from a second part of the instrument; and,

FIG. 5 is a second perspective view thereof.
